UNITED STATES PATENT OFFICE.

FIELDS S. PENDLETON, OF BROOKLYN, NEW YORK.

CONSTRUCTION OF SHIPS' HULLS.

1,255,784.

Specification of Letters Patent.

Patented Feb. 5, 1918.

Application filed July 25, 1917. Serial No. 182,766.

To all whom it may concern:

Be it known that I, FIELDS S. PENDLETON, a citizen of the United States, and a resident of the city of New York, borough of Brooklyn, in the county of Kings and State of New York, have invented a new and Improved Construction of Ships' Hulls, of which the following is a full, clear, and exact description.

10 This invention relates to ships and has particular reference to the construction of ships' hulls from the combination of wood and metal.

15 Among the objects of the invention is to construct a ship's hull easily and rapidly and at the same time provide for ample rigidity and strength.

20 Another object of the invention is to improve the interior construction of a ship's hull with respect to the amount of storage space provided and the facilities for access to all parts of the hull.

25 With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views and in which—

30 Figure 1 is a side elevation of a hull made in accordance with this invention, the middle portion being broken away to conserve space and with a portion of the side broken away to disclose the interior arrangement of the diagonal reinforcing straps.

35 Fig. 2 is a plan view of the same with a portion broken away to disclose the transverse metal deck beams.

40 Fig. 3 is a vertical transverse section showing more particularly the manner of construction of the hull and the interior spacing.

45 Fig. 4 is a vertical longitudinal section corresponding to the line 4—4 of Fig. 2; and

50 Fig. 5 is a detail perspective view corresponding to the upper right hand portion of Fig. 3 below the waist line.

From what has been indicated above it will be understood that this ship design is

intended for use in the rapid and cheap construction of ships' hulls in which the elements of strength and durability are associated favorably with maximum carrying capacity. I wish it to be understood, however, that I am not especially concerned with the exact type or form of hull indicated by the accompanying drawings, reserving the right to embody any or all of the features of the improved design in many different types of hulls in practice.

55 At 10 I indicate the hull as a whole having a stem 11, keel 12 and stern 13. Any suitable number of decks may be provided but I have indicated only upper and lower decks 14 and 15 each being provided with suitable hatches such as indicated at 16 and 17, the upper hatches each being provided with a coaming 18.

60 I refer now particularly to the construction of the hull. See Fig. 3. The main wooden frame structure includes a series of transverse ribs 19 of heavy construction across the bottom above the keel 12 and of somewhat lighter construction along the sides and merging at their upper ends on opposite sides of the hull into the waist 20. 65 These ribs are arranged relatively close together from bow to stern and occupy substantially vertical transverse planes. Extending longitudinally of the hull, and supported upon the heavy bottom portions of 70 these ribs are heavy and approximately rectangular stringers 21. Upon the central stringer is supported and secured a heavy metal eye beam keelson 22, and means for securing the keelson to the central stringer 21' including a series of metal fasteners 23 extending through the base flange of the keelson thence down through the stringer 21', the ribs, and into the keel. The central stringer 21' is additionally secured to the 75 ribs by means of an angle bar 24 upon one side, this angle bar being secured to the stringer by means of horizontal fasteners 25. Fastened to the keelson are angle-iron knees 22^a, 22^b at the bow and stern, respectively. 80 On opposite sides of the longitudinal center of the bottom or the stringer 21' the stringers may be spaced somewhat as indicated at 26 but outwardly thereof and around the bilges 27 the stringers are 85 arranged firmly and compactly. Along each 90

bilge the stringers 28 are grouped so as to occupy a diagonal plane spanning the rounded bilge portion of the ribs. Strong metal fasteners 29 pass directly through the 5 stringer members 28 to the outside of the hull. The character of these metal fasteners may vary somewhat under different circumstances but I prefer to use galvanized metal throughout, which enables these fasteners to be headed at one end and provided with nuts at the other or else adapted to be clenched over on the inside of the hull. The stringers 30 along the bottom and adjacent to the bilge stringers 28 may constitute 10 the floor of the hull but extending thence inwardly and over the spaced stringers 21 I provide preferably three inch planking 31 to constitute the main floor, this being applied after the main fasteners are used to 15 secure the ribs, stringers and outside planking together. The bilge portions of the bottom are provided with filler blocks 32 between the diagonally arranged stringers 28 and the curved portions of the ribs making 20 an unusually stiff and strong bilge structure with the bolts 29 passing through all of the parts. Each of the decks 14 and 15 comprises 25 transverse beams 33 supported at their outer ends upon angle bars 34, one flange of 30 which extends vertically on the inner face of the upper ends of the ribs while the other flange of each angle bar 34 projects inwardly toward the longitudinal center of the hull forming a direct support for the ends of the 35 metal beams 33. A shelf 35 is securely attached by means of bolts 36 beneath the beams 33 and assists to strengthen this part 40 of the hull and to support the beams. Each of the shelves is provided on its inner edge 45 with an angle beam belt 37 extending entirely around the inside of the vessel and held by the same bolts 36, the waterway 38 lying along the upper sides of the outer ends of the beams. Suitable wooden planking 39 is arranged longitudinally of the ship upon 45 the beams 33.

40 indicates a stanchion made mainly of hard wood and supported upon the metal keelson 22, the upper edge of the stanchion 50 carrying an I-beam 41 on which in turn the central portions of the transverse beams 33 are supported. Between the two decks 14 and 15 is another vertical longitudinal stanchion 42.

55 I now call attention particularly to Fig. 1 indicating at 43 diagonally arranged strong galvanized metal straps extending from a heavy belt 44 extending along the wales or sides of the hull. The straps 43 are secured 60 at their upper ends to the belt 44 and extend thence downwardly in diagonal lines forwardly and rearwardly across the bottom toward the strakes 45 adjacent to the keel.

These straps are secured together where they intersect one another and are also arranged 65 close against the outer edges or surfaces of the ribs 19 making therewith an unusually strong rigid structure of minimum weight. The outside planking 46 is secured longitudinally of the ship on the outside of the 70 net work of the straps 43.

I also call attention to the strong rigid bracing associated with the main stanchion 40 which bracing comprises diagonal intersecting straps 47 connected at their upper 75 ends to the bottom of the eye beam 41 and the angle bar 48 supporting the same upon the stanchion and at their lower ends the straps 47 are secured to the angle bar 24 at the keelson. At the intermediate portions 80 they are secured to the angle bar 49 at the bottom of the stanchion. Fastened to the ends of the beams 41 and 48 are angle-iron knees 41^a and 41^b at the bow and stern, respectively. 85

As shown in Fig. 5, in detail, each of the metal fasteners extending from the outside of the hull has its head countersunk at 50 and the cavity formed thereby is subsequently plugged as shown at 51 in any suitable manner to make a smooth exterior 90 finish. 95

I claim:

1. In a ship's hull, the combination of a 95 keel and a plurality of strakes extending along opposite sides of the same, of a series of ribs arranged upon and transversely of said keel and strakes, a heavy central stringer extending longitudinally of the ship across the ribs, a metal I-beam keelson 100 supported upon the central stringer, an angle bar secured to one side of the stringer and supported upon the ribs, auxiliary stringers on opposite sides of the central stringer, fastening devices passing through 105 the stringers, ribs and keel, certain of said fasteners passing through said angle bar, other of said fasteners passing through the bottom of the keelson securing it in place, a stanchion supported upon the keelson, and 110 metal bracing straps associated with the stanchion and secured at their lower ends to said angle bar.

2. In a ship's hull, the combination with a keel, strakes extending along the keel at 115 opposite sides thereof, transverse ribs supported upon the keel and strakes and a series of stringers extending longitudinally of the bottom of the hull upon the ribs, of a keelson in the form of a metal I-beam 120 supported upon the central stringer, a stanchion supported upon the keelson, a plurality of metal straps secured to the top of the stanchion extending thence diagonally across one another, and fastening devices 125 securing the lower portions of the straps

to the bottom of the stanchion and between certain of said stringers.

3. In a ship's hull, the combination of a series of transversely arranged parallel ribs having rounded bilge portions, a series of longitudinal stringers supported upon the bottom portion of the ribs, a series of

stringers arranged in a diagonal plane spanning each rounded bilge portion, filler blocks filling the space between the diagonal series 10 of stringers and the rounded bilge portions of the ribs, and metal fasteners passing through the stringers, ribs and filler block.

FIELDS S. PENDLETON.

Copies of this patent may be obtained for five cents each, by addressing the "Commissioner of Patents, Washington, D. C."
